(57) **CLAIM**

The ornamental design claim of a rodent trap, substantially as shown and described.

DESCRIPTION

FIG. 1 is a perspective view of an ornamental design for a rodent trap showing my new design;

FIG. 2 is a bottom view thereof;

FIG. 3 is a top view thereof;

FIG. 4 is a cross-sectional view through a plane at the center point thereof;

FIG. 5 is a right side view thereof;

FIG. 6 is a left side view thereof;

FIG. 7 is an end view thereof; and,

FIG. 8 is an opposite end view thereof.

Portions of the design shown in broken lines represent environmental subject matter and form no part of the claimed design.

1 Claim, 5 Drawing Sheets

FIG.2

FIG. 3

FIG.7
